UNITED STATES PATENT OFFICE

118,879

DESIGN FOR A LADY'S COAT

Max Kolmer, New York, N. Y.

Application December 19, 1939, Serial No. 89,000

Term of patent 3½ years

To all whom it may concern:

Be it known that I, Max Kolmer, a citizen of the United States and a resident of the city of New York, in the county of New York and State of New York, have invented a new, original, and ornamental Design for a Lady's Coat, of which the following is a specification, reference being had to the accompanying drawing, forming a part thereof.

Fig. 1 is a front view of a lady's coat showing my new design.

Fig. 2 is a rear view of the coat as shown in Fig. 1.

I claim:

The ornamental design for a lady's coat, substantially as shown.

MAX KOLMER.
